[57] CLAIM

The ornamental design for a push-up butter/margarine stick dispenser, as shown and described.

DESCRIPTION

FIG. 1 is a perspective view of a push-up butter/margarine stick dispenser showing our new design;

FIG. 2 is a side elevation view thereof, the remaining sides being identical;

FIG. 3 is a top plan view thereof;

FIG. 4 is a bottom plan view thereof; and,

FIG. 5 is a cross-sectional view taken along line 5—5 of FIG. 2.
